John Thompson, ATTORNEY

UNITED STATES PATENT OFFICE.

WILLIAM MONELL STANBROUGH, OF NEWBURGH, NEW YORK.

LOWER DENTAL PLATE.

Application filed April 23, 1927. Serial No. 185,996.

This invention relates to the manufacture and fitting of full lower dentures, and has for its objects the provision of a novel means embodied as a part of the lower denture where-
5 by the same may be made to provide not only a perfect fit when first made, but which can be readily adjusted or reshaped to compensate for the changes due to shrinkage of tissues.

10 In the making of lower dentures it has been the custom to construct them of hard rubber or other similar material, fitting the same to the impression which has already been taken after the extraction of the teeth,
15 and as it is at best a difficult matter to retain the lower denture in place at any time, it is essential that as perfect a seal be produced as possible, but in the usual practice, using a hard plate, as the tissue shrinks, the denture
20 must be refitted which can only be done by scraping or cutting away of the hard plate where required, which is not only of considerable work, but never produces as good a fit or seal as at first.

25 In my present invention I have overcome this difficulty by producing a lower denture that is provided with a piece of sheet metal such as gold, pure tin or other suitable material, which is embedded or cast as an insert
30 into the denture and which projects from the lower edge or lingual wall thereof in the form of a flange of semi-pliable material, capable of being formed or shaped by the proper instruments and designed to retain
35 such shape.

40 This insert may be in the form of several pieces, and located as desired, or it may be of one piece and extend around the plate, and downward below the mylo-hyoid ridge and back to the retro-molar triangle.

45 The object being that by the use of such a flange or extension of the denture, that it can be bent or formed to reduce pressure upon the soft tissue and conform more closely to the form or shape of said tissue in the desired locality, and thus produce a perfect seal as well as fit and as in this manner of fitting the plate or denture is not cut away the denture is rendered more staple and of greater
50 strength due to the reinforcement by the metal.

55 It will thus be seen that dentures of this construction can be fitted soon after the teeth have been extracted, and refitted from time to time as shrinkage takes place, thus pro-

ducing a more perfect fit without much labor or time in the fitting.

With these and other objects in view, my invention consists in certain construction and combination of parts as will hereinafter be 60 fully described and claimed, and illustrated in the accompanying drawings, which form a part hereof and in which like figures of reference refer to corresponding parts in all of the views, and it is understood that slight 65 changes may be made without departing from the spirit of the invention.

In the drawings:

Figure 1 shows a model of the lower jaw 10, and the mylo-hyoid ridge is indicated as 70 11, and the retro-molar triangle by the numeral 12.

Figure 2 shows a similar view of the model of the jaw, with the addition of the insert 75 13, placed in the same position as it will assume after being secured in the lower denture.

Figure 3 shows a lower denture with the insert 13 secured thereto.

Figure 4 shows one form of insert before 80 the same has been shaped.

Figure 5 shows the same insert after shaping.

Figure 6 shows a part of a jaw model, with the insert placed thereon. 85

Referring to the drawings:

In Figure 1 is shown a model 10 of the lower jaw, and indicated thereon is the mylo-hyoid ridge 11, and in my design it is desired to extend the plate below and back of 90 this ridge 11, so that a firmer structure of the denture will result, while this has been done in the past both with vulcanite and metal plates it has not been directed to the proper location.

95 In my present invention it is my intention to combine in the vulcanite base that is to serve as a lower denture, a plate or casting of the desired form and material, such as metal or other suitable material that will 100 serve to form a seal at the point of contact between the edge of the lower denture and the mucous membrane, thus resulting in "suction."

A very large proportion of lower dentures 105 are not extended to the mylo-hyoid ridge and do not have the aid of atmospheric pressure in their retention; this being so because the skill required to secure an accurate impression of this region is not possessed by all 110

dentists, also the change of shape of the alveola ridge, often results in a shifting of the lower denture thus permitting a leak as at 14, but if this part of the lower denture 5 15 be made of some substance such as pure tin, or gold that can be changed to conform to the needs of the case, a contact between the mucous membrane and the edge of the denture can be maintained, a seal assured 10 and atmospheric pressure will assure a more staple lower denture adding much to the comfort of the user.

In the further use of such extensions or 15 inserts 13 of a workable material as above described, and before being cast in the denture 15, they are formed to approximately fit the model 10 of the jaw for which they are intended, that is, the tissue of the locality 20 against which the adjusting means as represented by said insert 13 are to impinge, seeking to establish a "seal", one of such a character, namely, easily compressed, and occupying quite different positions when at rest and in use, that to achieve the full benefit 25 of the possibilities it might be advantageous to use a method of getting the proper adjusting of the "adjusting means", in the following way: to make the denture with the inserts 13 cast therein and in a semiformed 30 condition, and after fitting it to the jaw, to

place some material such as a wax, or other suitable material, upon the outer surface of said insert 13, and then by placing the denture in the mouth of the patient, a few hours wear and use, would conform the wax to a 35 working shape, then by using plaster of Paris or other means placed in contact with the wax extended sufficiently over the surface of the lower denture which covers the alveola ridge, a guide is secured that will serve to 40 conform the adjusting means or insert 13; or rubber may be vulcanized in the space occupied by the beeswax, and in this case the insert 13 form a support to hold the vulcanite, but in this case holes properly located and of sufficient size would have to be made in the insert 13 in the proper locality. 45

Having thus described my invention, what I claim as new and desire to secure by Letters Patent, is:

A lower denture of the class described, comprising in combination with a molded plate having teeth secured therein, of a sheet metal insert molded therein and depending therefrom and adapted to be formed to embrace 55 the mylo-hyoid ridge, forming a seal to retain said denture in place.

In testimony whereof I hereunto affix my signature.

WILLIAM MONELL STANBROUGH.
